UNITED STATES PATENT OFFICE.

ALTA NEWMAN, OF WEBSTER CITY, IOWA.

CALCULATING-MACHINE.

No. 890,168.

Specification of Letters Patent.

Patented June 9, 1908.

Application filed August 31, 1907. Serial No. 390,890.

To all whom it may concern:

Be it known that I, ALTA NEWMAN, a citizen of the United States, residing at Webster City, in the county of Hamilton and State of Iowa, have invented a certain new and useful Calculating-Machine, of which the following is a specification.

My invention relates to that class of calculating machines now in the market, and known as the "Burroughs adding machine," such for instance as Patent No. 504,963, issued to W. S. Burroughs on Sept. 12, 1893. In this connection it should be understood that the ordinary adding machine mechanism herein illustrated and described, is substantially the same as that shown in said patent, and operates in the same manner.

My object is to provide simple, and easily actuated means whereby an adding machine of the class described may conveniently and easily be operated for the purpose of subtracting. In this connection it is to be understood that in machines of the Burroughs type, the adding wheels operate only in one direction, and cannot be turned back for the purpose of subtracting. It is therefore my object to provide means whereby the adding wheels may be turned forward to the desired distance, and the total carrying devices be held inoperative during the subtracting process, so that the adding wheels that have been operated upon for subtracting purposes may be turned around until they stand at the proper positions for displaying the total which represents the original set of digits minus the total number subtracted therefrom.

My invention consists in the construction of the various mechanical features of my invention, and the arrangement and combination thereof with an adding machine of the type mentioned, and also in the arrangement of a set of digits upon the keys in addition to the usual digits, whereby the operator may conveniently and successfully use my improved device, as hereinafter more fully set forth, pointed out in my claims, and illustrated in the accompanying drawings, in which—

Figure 1 shows a detail sectional view of a part of an adding machine of the type mentioned, and having connected therewith devices embodying my invention. Fig. 2 shows a detail perspective view of the rack bar for actuating the adding wheels and connected parts, to illustrate some of the parts of

an ordinary adding machine with which my improvement is closely associated. Fig. 3 shows a detail edge view illustrating the means for connecting the lever that is operated by the releasing key, with the lever that trips the rack bar. Fig. 4 shows a plan view illustrating the key board, and the arrangement of the digits on the keys thereof, and Fig. 5 shows a detail sectional view showing a modified form of the device for holding inoperative the carrying mechanism.

In the accompanying drawings, I shall set forth so much only of the construction and function of the adding mechanism as is necessary for a full understanding of the arrangement and combination with it, of the mechanism for use in subtracting.

The reference numeral 10 indicates the casing and 11 the keys mounted therein, and arranged in rows of nine each, one row for each column of figures to be added. Each of these keys is arranged over a bell crank lever 12, and connected with each bell crank lever is a rod 13. These rods all stand adjacent to a notched bar 14, and when any of said keys is depressed, the rod 13 enters one of the notches of the bar 14. Slidingly mounted adjacent to each notched bar 14 is a rack bar 15 having a shoulder 16 at one side of its upper end, and a shoulder 17 at the other side of its upper end. It is also provided with a stop pin 18 and a slot 19.

The reference numeral 20 indicates one of the adding wheels connected with a lever 21. The operation of the rack bar during its initial movement is substantially as follows: When a key is depressed, the trip lever indicated by the numeral 22 is moved by mechanism not herein shown, so that its lug 23 passes out of engagement with the shoulder 17, whereupon the rack bar 15 may be moved downwardly as hereinafter described, until its shoulder 16 strikes upon the rod 13 that is in one of the notches of the bar 14. Thus, the downward movement of the rack bar is limited by the rod 13 of the key which is depressed. At one side of the machine is a crank 24 connected by mechanism not shown, with the lever 25, which lever is attached to the rack bar 15 by means of a pin 30, which projects through the slot 19 of the rack bar. In this way, the rack bar is operated by the crank 24. The lever 25 is connected with the lower end of the rack bar by means of a contractible coil spring 31, which spring tends to hold the lever 25 in position.

with the pin 30 at the bottom of the slot 19. The first effect of a manipulation of the crank 25 is to operate the adding wheels and move them out of mesh with the racks. 5 Then the racks are moved downwardly and brought into engagement with the adding wheels and thereafter, the racks are elevated and the adding wheels turned. The mechanism for accomplishing these results is not 10 herein fully disclosed, but is substantially the same as that illustrated and described in the said Burroughs patent.

The outward movement of the rack bar 15 is limited by means of a lever 32, which is 15 pivoted at 33, and which normally stands in the path of the pin 18, hence the pin 18 will strike upon the bottom of the lever 32, and the rack will stop. The lever 25 however, 20 will move outwardly until its pin 30 reaches the top of the slot 19 which will apply a considerable tension to the spring 31.

In the operation of adding on a machine of this kind, and in the event that the movement of the rack bar 15 is sufficient to bring 25 the adding wheel past the ninth tooth thereof, then it is necessary that the adding wheel be actuated far enough to move the adjacent adding wheel one tooth space for the purpose of carrying a total. This is ordinarily 30 accomplished in substantially the following manner: Connected with the adding wheel 20 is a lug 34 adjacent to the ninth tooth of the adding wheel. Arranged in the path of this lug 34 is a lever 35 designed to be 35 tripped by the said lug. This lever 35 carries an arm 36 which arm normally stands in the path of a lug 37 which is placed on a lever 38, which lever is normally held by a spring 39 in a direction toward the lever 35, and the 40 lever 35 is normally held by a spring 40 in position where its arm 30 will engage the lug 37, there being a stop 41 to hold the lever 35 in said position. There is only one way provided for moving the trip lever 32 out of the 45 path of the pin 18, and this is done by means of the lever 38 striking upon the lever 32.

In Fig. 3 of the drawings, I have shown a pin 42 fixed to the lever 38 to strike against the lever 32. Hence, in order to move the 50 adding wheel past the ninth tooth so that the total will be carried to the next adding wheel, it is necessary for the lug 34 to operate the lever 35 so as to throw the arm 36 below the lug 37, and thus permit the lever 35 to strike 55 upon the lever 32 to throw the lever 32 out of the path of the pin 18, and then permit the spring 31 to move the rack bar outwardly one additional tooth space. Obviously, if the lever 38 is held against an inward movement when the lever 35 is operated by the 60 lug 34, then the total will not be carried from one adding wheel to the next, but the adding wheel will rotate as far as it is actuated by the rack bar 15 without in any way affecting 65 the adjacent adding wheels. I have pro-

vided means for holding each lever 38 in an inoperative position when it is desired to use the machine for subtracting, and this I have accomplished by means of a sliding key bar 43 mounted in the frame 10 to engage an arm 70 44 on the lever 38. This key bar 43 is provided with a spring 45 for elevating it, and obviously, when an operator presses upon the key bar 43, the adding wheel in the particular column in which the key is included will 75 be operative only for the purpose of turning around, but the carrying mechanism of that particular column will be rendered inoperative. That is to say, the adding mechanism is not in anyway affected by the key bar 43, 80 but when the key bar 43 is depressed, the carrying mechanism is held inoperative.

I have illustrated a modified form of the device in Fig. 5 of the drawings, for holding the lever 38 inoperative, which mechanism is 85 as follows: Mounted in the side of the frame is a spring actuated key bar 45 connected with a bell crank lever 46. This bell crank lever is formed with a hook 47 designed to engage a pin 48 on the lever 38, hence when 90 said key bar 45 is pushed in, the hook 47 will engage the pin 48 and prevent an inward movement of the lever 38, and when the key bar 45 is released, its spring will hold the hook 47 out of the path of the pin 48. 95

In order that subtracting may be rapidly and accurately accomplished by the use of the devices for throwing the carrying mechanism out of operation, I have arranged the key board in the manner shown in Fig. 4. 100 On the first column to the right, the large digits beginning with 1 at the bottom of the column, and ending with 9 at the top of the column, indicate the digits ordinarily placed on keys of machines of this kind for designating the amount that each adding wheel will be moved when any given key is depressed. And on this column of keys, I have placed in small letters on the upper key, the digit 1 and the other consecutive digits up to 9 on the remaining keys in the column. On the second column from the right, the upper key is provided with the small digit 0, the next key with the digit 1, and the lower key with the digit 8, the others being consecutively arranged between them. All of the other keys in the column to the left of the one last mentioned are arranged the same as in the second column. By this arrangement of digits on the keys, the operation of the device in subtracting is as follows: Assuming that the keys in the first three columns have been actuated so that the adding wheels represent a total number of 888, and it is desired to subtract from this number the sum 129. In 115 subtracting, the operator uses the small set of digits on the keys, and in the instance above referred to he first depresses the key showing a small 9 on the column at the right, then the key bearing the small 2 on the sec- 120 125 130

ond column to the right, then the key bearing the small 1 on the third column to the right. At the same time, he depresses the key bar 43 for the third column and holds it down while 5 turning the crank at the right of the machine, to thereby prevent totals being carried to the left of the third column, but the total carrying mechanism of the other two columns to the right is not in any way interfered with.

10 Then when the adding wheels have been actuated as before described, the adding wheels of the first three columns stand as follows: The first wheel will be turned one tooth space because the digit 1 is the one shown in large 15 type on the key that was first depressed, thus leaving this adding wheel in position with the digit 1 thereof in position for adding, instead of the digit 8, that was previously in said position. The second wheel will be 20 moved seven tooth spaces because the digit 7 appears in large type on the key that was depressed in said column, hence this second wheel will be turned so that the digit 5 will appear in adding position on it, because it 25 will have been turned seven tooth spaces which is the digit that appeared on the second key that was depressed, thus resulting in turning said second adding wheel around until the digit 5 appeared in adding position.

30 Furthermore, the third adding wheel will be moved one tooth space by the carrying mechanism during the time that the second adding wheel is being actuated, thus placing the third adding wheel in position with the 35 digit 9 thereon in adding position, and when the key bearing the small numeral 1 in the third column is depressed, the adding wheel will be moved eight tooth spaces, which will leave it in position with the digit 7 in adding 40 position so that on the three adding wheels at the right, the digit 785 will be in adding position, which represents the number originally on the wheels, 888 minus the number 129 which was subtracted from it. This ar- 45 rangement of the small digits on the keys will operate accurately for purposes of subtracting in all cases except where the number to be subtracted has an 0 at the right of the number, and when this occurs, it is nec- 50 essary for the operator to depress the key above the one he would ordinarily have depressed, in the example as first given, which will result in bringing an accurate total. As an instance of this exception to the general 55 rule, we will assume that the number originally appearing upon the adding wheels was 888, and that it was desired to subtract from it 120. No key in the first column to the right need be depressed, as the digit 0 does 60 not appear on said first set of keys. In the second column to the right, instead of de- 65 pressing the key with the small 2, the key above it should be depressed, thus causing the second adding wheel to move eight tooth spaces instead of seven, which is the number

it would move if the key bearing the small 2 had been depressed. Then the key bearing the small 1 of the third column is depressed, which will result in turning the adding wheels so that the digit 768 appear thereon, which represent the original number of 888 minus the 120 subtracted. It is not at all difficult for the operator to remember this exception, because the 0 does not appear in the first column to the right, but it does appear in all 70 of the other columns, so that when a number has a 0 at the right, the operator cannot de- 75 press any key in the first column to the right, and thus his attention is called to the fact that in the next key depressed, he must de- 80 press the key above the one he would ordi- 85 narily depress if there were no 0 at the end of the number he is subtracting.

Having thus described my invention, what I claim and desire to secure by Letters Patent 85 of the United States, therefor, is—

1. In a calculating machine, the combination of a number of adding wheels, a total carrying mechanism for each adding wheel comprising a cam connected with the adding 90 wheel, a rack, a spring for normally elevating said rack, a pin connected with the rack, a lever pivoted at its upper end and having its lower end normally in position to engage said pin and prevent upward movement of the 95 rack, a bell crank lever arranged in position to be engaged by said cam, means interposed between the bell crank lever and the first mentioned lever whereby the first mentioned lever is normally retained within the path of 100 the pin on the rack, and whereby when the bell crank lever is operated by the cam, the first mentioned lever may be moved out of the path of the said pin, a spring actuated 105 key, and means interposed between the key and said lever, whereby when the key is de- 110 pressed, the lever will be held in the path of the pin, irrespective of the movement of said bell crank lever.

2. In a calculating machine, the combination of a number of rows of key bars; each row bearing consecutively arranged digits beginning with 1 and ending with 9, and a second set of digits on each row, the digits on the first row to the right being consecutively 115 arranged, and beginning with 1 on the 9 key and ending with 9 on the 1 key, and the second set of digits on each of the other rows of keys beginning with 0 on the 9 key and ending with 8 on the 1 key, adding mechanism 120 arranged to be actuated by said keys, total carrying mechanism arranged for automatic operation by the adding mechanism, and a key bar arranged for holding the carrying mechanism inoperative.
